ELECTRICAL MERCURY CUT-OUT

Horace Worsdall, Bedford, England, assignor to himself and John Craig Harvey and Andrew Harvey, both of London, England

Application October 21, 1931, Serial No. 570,205
In Great Britain December 23, 1930

14 Claims. (Cl. 200—113)

This invention relates to electrical cut-outs of the kind in which there is employed a column of mercury which normally forms an electrical connection between two contacts and is contained 5 in a tube of insulating refractory material having a restricted bore in a portion thereof, in which the mercury parts when there is a predetermined overload of current.

According to this invention a mercury cut-out 10 comprises a refractory body having a comparatively narrow or restricted bore in said body, said bore being adapted to receive a thread or column of mercury normally forming an electrical connection between two contacts, a reservoir of mercury beneath said bore, and a plunger mechanism 15 associated with said reservoir whereby upon operation of said plunger mercury may be driven up from said reservoir into said bore to recomplete the electrical circuit.

20 It will be seen that the construction of mercury cut-out in accordance with this invention avoids the use of rubber bags and similar devices which have hitherto commonly been employed in mercury cut-outs and provides a cut-out which is 25 electrically sound, simple and durable.

In constructions of cut-out in accordance with this invention and suitable for use for larger sizes the narrow or restricted bore in the refractory material preferably forms part of a closed path 30 for the mercury the plunger mechanism being associated with said closed path so that when an overload occurs and a break is caused in the thread or column of mercury in the restricted or narrow bore this thread or column may be re- 35 completed by operation of the plunger the said operation causing mercury to flow round the closed path.

Preferably the cut-out is enclosed in a casing of non-conducting material through which the 40 contacts making connection to either end of the operating thread or column of mercury project.

The invention is illustrated in the accompanying drawings which show various arrangements in accordance therewith.

45 Figure 1 is a vertical sectional view of one embodiment of the invention, parts being shown in elevation;

Figure 2 is a view in rear elevation of the embodiment shown in Figure 1;

50 Figure 3 is a horizontal sectional view taken on the line 3—3 of Figure 1;

Figure 4 is a vertical sectional view of a modified form of cut-out embodying the invention, 55 parts being shown in elevation;

Figure 5 is a view similar to Figure 4 showing a further modification;

Figure 6 is a vertical sectional view of a further modification, parts being shown in elevation;

Figure 7 is a view in vertical section of a modified form of pressure creating mechanism; 60

Figure 8 is a view similar to Figure 7 showing an additional modified form of pressure creating mechanism;

Figure 9 is a vertical sectional view of a further modification of pressure creating mechanism; 65

Figure 10 is a vertical sectional view of a still further modification of pressure creating mechanism; 70

Figure 11 is a vertical sectional view of an assembled cut-out constructed in accordance with the invention with parts shown in elevation;

Figure 12 is a fragmentary view in front elevation of an assembly in which a plurality of cut-outs is provided with common operating means; 75

Figure 13 is a top plan view of the construction shown in Figure 12;

Figure 14 is a view in front elevation of an assembly in which a plurality of individual cut-outs is mounted on a control panel; 80

Figure 15 is a transverse vertical sectional view of the construction shown in Figure 14.

Referring to Figures 1, 2 and 3 of the drawings which show in sectional elevation, rear elevation, 85

and sectional plan on the line 3—3 of Figure 1, one form of construction the cut-out here shown

comprises a refractory body 1, having two bore holes formed therewithin one of said bore holes

having a restricted portion 2. This restricted 90

portion is adapted to contain the thread of mercury which is broken when too high a current flows therethrough. The two bores in the refractory body are indicated by the reference nu-

mbers 3 and 4, the bore 3 containing the re- 95

stricted portion 2. The bores 3 and 4 communi-

cate at the bottom so that in effect a reservoir of mercury beneath the bores is obtained. The lower communication between the bores is indi-

cated at 5. The refractory body 1 is fitted into an 100

insulating tube 6 which screws at one end into a metal cap 7 and at the other into a second metal cap 8. As will be seen the metal cap 7 forms as it

were the bottom of the mercury reservoir, and also forms in effect one wall of the communicating 105

passage 5. The metal cap 8 is formed with two bore holes, as shown, these bore holes communi-

cating via the passage 9. Into one of the bore holes in the metal cap 8 is fitted a plunger 10

which is mounted upon a rod 11 adapted to be 110

depressed by a push button 12, the rod passing through a bearing member 13 screwed into the metal cap 8, the plunger being mounted for free sliding movements for creating pressure in the conduit. The other bore hole is closed at the top by a screwed plug 14. The whole device is enclosed and protected by an insulating shroud or cover 15 which is formed with a pair of apertures on its top face to pass the push button 12 and the rod 11 and upper portion of the bearing member 13. As will be seen a spring 16 surrounds the rod 11 and serves to bias the plunger 10 upwards. Contact to the bottom of the mercury thread or column is made by means of a plug or similar connection device 17 passing through the shroud as shown and held against the cap 7 by a screw 18 screwing into the said cap. Connection to the other end of the mercury thread or column is made by means of a cable (not shown) in the circuit to be controlled, said cable being passed through a suitable aperture in the shroud into a recess or socket 19 formed in the cap 8 and its bared end clamped by the usual grub screw 20. It will be seen that with this arrangement if the overload operates the mercury column may be re-completed merely by depressing the push button 12 which will move the plunger 10 downwardly to create pressure in the conduit 4, the pressure acting on mercury in the reservoir to force mercury up into the restricted bore 2. Figure 4 shows an arrangement generally similar to that illustrated in Figure 1 the principal difference being that in Figure 4 the bore 3 is not provided with a restricted portion but is made of the required diameter substantially throughout the whole of its length while a float or non-return valve 21 is situated above the end of the bore in the refractory body 1. A further difference is that the plunger 10 operates not directly in a bore hole 22 formed in the cap 8 but in an insulating lining 22 positioned in said bore. 23 is an air vent which may be provided if desired not only in the construction shown in Figure 4 but in any other construction. In Figure 4 the air vent 23 appears to be stopped at its outer end by the insulating shroud 15 but in practice the fit of the shroud about the assembled body of the cut-out is not sufficiently close to result in air-tightness. Figure 5 shows a further modified construction generally resembling Figure 4 but differing therefrom principally in that the upper connecting passage 9 is omitted. In this arrangement the mercury column is re-completed after the cut-out has "tripped" as in the previously described arrangement and in practice it is found that satisfactory operation can be obtained without providing a closed or loop path for the mercury.

In all the constructions of mercury cut-out illustrated a certain amount of back pressure resulting upon the plunger 10 will be generated when the mercury column is broken by an overload. This back pressure may be employed to give an indication that the overload has operated by so arranging the parts so that the back pressure can "kick-back" the plunger 10 and push button 12 to a position higher than that occupied before operation, the plunger being held in this "kick-back" or higher position by friction. The form of construction illustrated in Figure 5 in which a closed or loop circuit for the mercury is not provided, is not so suitable for the larger sizes of mercury cut-out as are constructions, such as those illustrated in Figures 1 to 4.

Figure 6 shows in sectional elevation a simple form of construction suitable for use in small

sizes of mercury cut-out. In this construction the assembly consisting of the refractory body 1, tube 6, valve 21, plug 14, and end cap 8a (which is screwed on to one end of the tube 6) is screwed by means of a thread formed on the other end of the tube 6 into a base-piece 7a into which also screws a plunger assembly as shown. This form of construction offers the advantage that the plunger assembly may be arranged quite conveniently at a considerable distance from that part of the apparatus in which the column or thread of mercury is situated. Where the circuit to be controlled is at a high voltage this arrangement presents obvious advantages of safety and in such cases the cylinder in which the plunger operates should be made of glass or other suitable insulating material.

In several of the structures in accordance with this invention and more particularly in structures such as those illustrated in Figures 5 and 6 where there is no loop circuit for the mercury, it is desirable to provide means for preventing the mercury column or thread from being broken after having been re-completed when the button is released after the re-setting operation. Referring, for example, to Figure 4 it will be seen that just as the push button is pressed the mercury is forced into the bore in the refractory body, so, when the button is released, there is a tendency for the mercury to be sucked out of said bore. This difficulty may be met in numerous ways. For example, in the arrangement shown in Figure 6 the cylinder 24 in which the plunger 10 moves is enlarged over a portion of its length as shown, the narrow portion (which fits closely about the said plunger) being of lesser length than the stroke. When in this construction the push button 12 is depressed pressure will be transmitted to the mercury through a certain amount of air which will be present (which air will, of course, be compressed on depression of the push button 12) and the mercury will accordingly be forced into the narrow bore. When, however, the push button 12 is fully depressed the plunger 10 travels beyond the close fitting portion of the cylinder in which it works and accordingly permits the trapped compressed air to escape past the said plunger and out through the air hole 23. Other arrangements of plunger mechanisms for serving the same purpose are shown in Figures 7, 8 and 9. In Figure 7 the push button 12 is formed in two parts 12a, 12b which are spring biased by means of springs 12c away from one another, the separation being limited by set screws 12d as shown. A bore hole 11a is formed through the rod 11 this bore hole communicating with a similar bore hole 10a in the plunger. It will be seen that with this arrangement when the push button 12 is depressed the air escape passage which is via the bore holes 10a 11a and then out between the parts 12a and 12b will be closed, but when the downward pressure of the finger ceases the air escape passage is opened. In the modified form shown in Figure 8 a similar effect is obtained, but in this case the push button is of simple construction, and is merely provided with a small hole or bore 12e communicating as before with bore holes 11a and 10a. When the finger is placed over the push button 12 to depress it, the upper end of the bore hole 12e is closed (by the finger) but the air escape passage is opened upon release when the finger is removed. In the arrangement shown in Figure 9 the cylinder is formed with peripheral groove 25 and the plunger is so shaped

150

that when the push button 12 is depressed so that the plunger is moved past the peripheral groove 25 compressed air can escape from one side of the plunger to the other via the said groove. The 5 peripheral groove 25 also permits the transfer of mercury from the upper to the lower side of the plunger during the upward stroke of said plunger in the case in which the plunger mechanism is employed in a cut-out having a loop or closed 10 path for the mercury (the case envisaged in Figure 9).

In certain cases, more especially in very small sizes, it is not necessary to provide means for 15 overcoming this suction effect it being sufficient to provide a simple plunger with limited travel. A simple arrangement of plunger mechanism without special means of air escape is illustrated in Figure 10.

Figure 11 shows in schematic sectional elevation 20 an assembled cut-out in accordance with the present invention arranged in a suitable box or container and adapted to be operated by a tumbler switch handle 26. This construction is very suitable for use in connection with double pole 25 arrangements in which case two mercury cut-outs side by side may be arranged within the box and their operating push buttons connected together by a transverse link which is operated by the tumbler switch. A somewhat similar multiple 30 mercury cut-out assembly in which the cut-outs are operated in common is shown in Figures 12 and 13 which figures show an arrangement of three phase circuit breaker there being provided three mercury cut-outs with their operating push 35 buttons linked together and to a master button ME.

Mercury cut-outs in accordance with this 40 invention are exceedingly small and compact, for example, Figures 12 and 13 show full size a three phase circuit breaker suitable for use for sizes up to about 20 amperes. This small size makes 45 the cut-outs very convenient for arrangement in banks for control of a plurality of circuits. A control panel incorporating a number of mercury cut-outs is shown in Figures 14 and 15, 27 being a glass front. If, as is preferable, the mercury cut-outs employed in a control panel of this kind are so constructed that the push button 50 operating knobs will be forced upwards by back pressure when over-load occurs, it will be possible to see at a glance the failure of any circuits.

Although the particular forms of mercury cut-out hereinbefore described are of the type in 55 which the mercury thread or column which is adapted to be broken upon overload is heated directly by the passage of current therethrough obviously the invention is not limited to cut-outs of this type. This type is preferred because of its greater simplicity but, if desired, (for example in the case of very large sizes or in cases where a delay or lag in operation is required) the mercury thread or column may be heated indirectly as by a heating coil arranged in any 60 convenient way and adapted to receive the operating current. Such a heating coil is indicated at HC in Figure 6. It will be obvious to those skilled in the art that indirect heating may be resorted to in any construction in accordance 65 with this invention in a similar manner, and that other arrangements in a heating coil are possible.

It will be noted that it is possible to employ a 70 cut-out in accordance with this invention as a switch by suitably operating the plunger push

button so as to obtain a suction effect sufficient to break the mercury thread or column although in all cases the thread or column will not be broken if the plunger push button is merely depressed and released as is the usual operation for re-setting.

It will further be noted that the U-tube like construction employed in the illustrated embodiments of this invention enables the convenient utilization of relatively long cores and the adoption of designs in which the voltage distribution in the cut-out is such as to render it safe and suitable for high tension working. Further, when the mercury column or thread breaks on over-load the gases generated can not only escape upwards but also expand downwards and into the plunger cylinder.

What I claim is:—

1. A mercury cut-out comprising a body of insulation having a first bore provided with a relatively narrow portion or constriction intermediate its ends, electrical contact members in electrical connection with the interior of said bore at points above and below the narrow or constricted portion thereof, a mercury reservoir beneath said bore, a conduit additional to said bore for transmitting pressure to said reservoir for driving mercury from said reservoir into said bore to electrically connect said contact members, and a plunger mechanism comprising a plunger mounted for free sliding movements in said conduit for creating pressure therein, said conduit, reservoir, and bore together forming a U-tube of which the said reservoir forms the bottom limb of the U, said conduit forming one of the remaining limbs and said bore the other limb, said plunger being free to be driven upwards in said conduit when pressure is generated as a result of rupture of the mercury column which normally makes connection between said electrical contact members. 95

2. In a mercury cut-out as set forth in claim 1, having a path for mercury interconnecting the upper ends of the limbs of said U tube, whereby there is formed a closed loop path for mercury. 100

3. A mercury cut-out as set forth in claim 1 and wherein the conduit consists of a second bore in the said body, said body having a path for mercury interconnecting the upper ends of the two bores therein whereby there is formed a 105 closed loop path for mercury. 110

4. A mercury cut-out comprising a body of insulating material having therein a first bore provided with a relatively narrow portion or constriction intermediate its ends, a non-return valve located at the upper end of said bore and forming when seated a closure for said bore, electrical contact members in electrical connection with the interior of said bore at points above and below the narrow or constricted portion thereof, a mercury reservoir beneath said bore, a conduit additional to said bore for transmitting pressure to said reservoir for driving mercury from said reservoir into said bore to electrically connect said contact members, and a plunger mechanism comprising a plunger mounted for 115

free sliding movements in said conduit for creating pressure therein, said conduit, reservoir, and bore together forming a U-tube of which the said reservoir forms the bottom limb of the U, said conduit forming one of the remaining limbs and said bore the other limb, said plunger being free to be driven upwards in said conduit when pressure is generated as a result of rupture of the mercury column which normally makes 120

125

130

135

140

145

150

connection between said electrical contact members.

5. A mercury cut-out as set forth in claim 1 including means for releasing air pressure accumulated during movement of said plunger in said cylinder to recomplete the mercury column in the bore.

6. A mercury cut-out as set forth in claim 1 including means having a passage leading from the outside air to the pressure face of the plunger, and means operable automatically upon depression of said plunger for closing said passage for releasing air pressure accumulated during movement of said plunger in said cylinder to recomplete the mercury column in the bore.

7. A mercury cut-out as set forth in claim 1 including means having a bypass leading from the pressure face to the rear face of the plunger, said bypass being positioned to function when said plunger is approaching its fully depressed position to release air pressure accumulated during movement of said plunger in said cylinder to recomplete the mercury column in the bore.

8. A mercury cut-out comprising a body of refractory insulating material having a narrow bore therein, contact means for making electrical connection with the interior of said bore at opposite ends thereof, a mercury reservoir attached to the lower end of said body and communicating with the bore therein, a conduit communicating with said reservoir for transmitting pressure to said reservoir for driving mercury from said reservoir into said bore, said conduit, mercury reservoir, and bore together constituting a U-tube structure of which the said reservoir forms the bottom limb of the U, said conduit forming one of the remaining limbs and said bore forming the third limb, a plunger mechanism comprising a plunger mounted for free sliding movements in said conduit for creating pressure therein, said plunger being free to be driven upwards in said conduit when pressure is generated as a result of rupture of the mercury column in said bore.

9. A mercury cut-out comprising means including a body of insulation having a bore provided with a relatively narrow portion or constriction intermediate its ends, electrical contact members in electrical connection with the interior of said bore at points above and below the narrow or constricted portion thereof, a mercury reservoir beneath said bore, a conduit additional to said bore for transmitting pressure to said reservoir for driving mercury from said reservoir into said bore to electrically connect said contact members, and a plunger mechanism comprising a plunger mounted for free sliding movements in said conduit for creating pressure therein, said conduit, reservoir, and bore together forming a U-tube of which the said reservoir forms the bottom limb of the U, said conduit forming one of the remaining limbs and said bore the other limb, said plunger being free to be

driven upwards in said conduit when pressure is generated as a result of rupture of the mercury column which normally makes connection between said electrical contact members.

10. A mercury cut-out as set forth in claim 8 and including a non-return valve at the upper end of the bore containing the mercury column, said valve when sealed forming a closure for said bore.

11. A mercury cut-out as set forth in claim 4 and having a path for mercury interconnecting the upper ends of the limbs of said U-tube whereby there is formed a closed loop path for mercury.

12. A mercury cut-out as set forth in claim 4 including means for releasing air pressure accumulated during movement of said plunger in said cylinder to recomplete the mercury column in the bore.

13. An electrical cut-out of the class described, including an insulating tube of narrow bore, a mercury column filling said bore, a metallic piece at each end of the tube in electrical contact with the corresponding end of the mercury column, a metallic contact member engaged with each metallic piece and serving to connect the mercury column in an electrical circuit to be controlled by the cut-out, a chamber in free communication with one end of the bore of the tube and into which mercury is expelled from the tube when the mercury column is ruptured due to the current in the electrical circuit exceeding a predetermined maximum value, means, independent of the action of gravity and operative while the cut-out is maintained in its normal position, for positively forcing mercury discharged into said chamber by rupture back into the tube and means for positively preventing return of mercury to the tube until said forcing means is operated.

14. An electrical cut-out of the class described comprising an insulating tube of narrow bore, a mercury column filling said bore, a metallic piece at each end of the tube in electrical contact with the corresponding end of the mercury column, a metallic contact member engaged with each metallic piece and serving to connect the mercury column into an electrical circuit to be controlled by the cut-out, a chamber in free communication with one end of the bore of the tube and into which mercury is expelled from the tube when the mercury column is ruptured due to the current in the electrical circuit exceeding a predetermined maximum value, an extension of said chamber arranged laterally of said insulating tube and communicating with that end of said tube remote from the main expansion chamber, means independent of the action of gravity and operative while the cut-out is maintained in its normal position, located in said extension for positively forcing mercury back into the tube and means for preventing return of mercury to the tube until said forcing means is operated.

HORACE WORSDALL.
